HIGH FREQUENCY SYSTEM

Alfred Wiessner, Berlin, Germany, assignor to
 C. Lorenz Aktiengesellschaft, Berlin-Tempel-
 hof, Germany, a company

Application March 8, 1938, Serial No. 194,555
 In Germany March 12, 1937

1 Claim. (Cl. 179—15)

The invention relates to high frequency systems, and particularly to high frequency intelligence transmission over cables.

The transmission of messages by means of high frequency alternating currents is well known. However, the frequency of the transmitted carrier is limited since the attenuation of the alternating message currents travelling along a cable is strongly increased with frequency, from which follows that transmission becomes impossible above a given frequency range.

The present invention consists in certain features of novelty which will be fully understood from the following description and be pointed out in the appended claim, reference being made to the accompanying drawing, in which—

Fig. 1 diagrammatically illustrates different curves of attenuation in response to frequency, while Fig. 2 is a diagrammatical representation of an arrangement according to the invention.

Referring first to Fig. 1, the continuous curve I shows the attenuation of a two-conductor line of a cable which is employed for high frequency intelligence transmission. The attenuation is plotted in dependency upon frequency. It is a well known measure to combine the two-conductor lines of a cable to phantom circuits (four-wire units, eight-wire units and the like) in order to provide a larger number of channels for the low frequency message transmission and to employ these channels for message transmission independently of the side or component circuits. However, this is possible under such conditions only that the circuits used for forming such phantom units are provided with corresponding balancing means. For the purpose of utilizing the phantom circuits also in connection with cables without compensation with respect to the four-wire units, it is proposed to provide another frequency range for the phantom circuits.

The invention, therefore, proposed to combine the side or component lines to phantom circuits (four-wire units, eight-wire units, etc.) also in

cables which are adapted for high frequency communication and to effect intelligence transmission thereover at a frequency which is higher than that employed on the side circuits. The dashed curve II of Fig. 1 shows an attenuation curve which has been obtained in a test with side circuits combined to a four-wire unit, for example. The frequency of the alternating carrier currents traveling along the side circuits is then located in the range between the points *a* and *b* of the frequency spectrum, while the frequency range between the points *c* and *d* is employed for transmission along the combined side circuits.

The pertaining circuit diagram is shown in Fig. 2. Two two-wire lines AB and CD of a high frequency conduction cable associated with the repeaters 1, 2, 3 and 4 are connected as a phantom circuit through the repeaters 5 and 6. The message transmission is effected over this circuit at a frequency which is higher than that of the side circuits, so that cross-talk freedom is not necessarily required between the four-wire units and said circuits, on the contrary, the alternating message currents may be separated in filter devices or the like according to any known methods. It is possible to combine four-wire units to eight-wire units in the same manner as above described.

What is claimed is:

The method of message transmission over physical cable pairs utilizing high frequency oscillations which includes the steps of connecting the cable pairs in phantom, impressing high frequency signalling oscillations on each pair as side lines; impressing other high frequency signalling oscillations on the phantom pairs, the lower frequency limit of said other oscillations being chosen above the upper frequency of the first oscillations at which said upper frequency the side lines approach maximum attenuation.

ALFRED WIESSNER.
